UNITED STATES PATENT OFFICE.

GEORGE F. EVANS, OF NORWAY, MAINE.

CLIPPING THE HAIR OF HORSES.

Specification forming part of Letters Patent No. 44,171, dated September 13, 1864.

To all whom it may concern:

Be it known that I, GEORGE F. EVANS, a resident of Norway, in the county of Oxford and State of Maine, have invented a new and useful or Improved Machine for Clipping the Hair of Horses or other Animals, or for Shearing the Wool of Sheep; and I do hereby declare the same to be fully described in the following specification and represented in the accompanying drawings, of which—

Figure 1 is a top view, Fig. 2 a front elevation, Fig. 3 a longitudinal section, and Fig. 4 an end elevation, of it.

In such drawings, A denotes the frame of the machine as having a handle, B, projecting rearward from it, and provided with a standard, C. A stationary plate, knife, or shear, D, is fastened to the under side of the frame A, and operates with a rotary series of shears, as seen at E. The journals of the said rotary shear or series of shears are supported in hangers in the uprights *a a* of the frame A, which uprights also support a horizontal shaft, F, provided with a crank, G, which is fixed on one end of such shaft F. Near its other extremity the shaft F has a gear, H, which engages with a pinion, I, fixed on one end of the rotary shear E. By revolving the shaft F by means of the crank the rotary shear will be put in revolution so as to cut off any hair when interposed between it and the edge of the stationary shear. Each of the blades of the rotary shear I prefer to arrange a little diagonally, as shown in the drawings, in order that it may cut with a drawing stroke or like one blade of a pair of scissors with respect to the other blade thereof. An adjustable gage or comb, K, extends along in front of and underneath the stationary shear, and is secured to the uprights *a a* by clamping-screws *c c*, which go through slots in the gage and respectively screw into the uprights. Furthermore, the cranked shaft F has a grooved pulley or wheel, L, placed on it so as to be capable of freely revolving on and independently of it. A chain or line, M, is attached to the pulley, and is wound around it several times, and from it is carried through the eye *d* in the upper part of the standard C, and afterward is fastened to a knob or short bar, N. A spiral spring, O, (coiled around the shaft F), has its inner end fastened to a stud projecting from one side of the pulley,

the other end of the spring being affixed to the frame A. (See Fig. 4.) The pulley carries a spring pawl, R, which rests on the periphery of a ratchet, S, fixed on the shaft F, the whole being arranged as shown in the drawings. By laying hold of the knob or bar N and drawing it quickly backward not only will the wheel L be revolved, but it will force the pawl against the ratchet, and so as to cause the shaft F to revolve and to produce through the intervention of the gears a quick rotary motion of the rotary shear. During the revolutions of the wheel L the spring will be wound up or coiled closer, so that on relieving the line from the draft of the hand such spring will be free to and will revolve the wheel, in an opposite direction and will rewind the line on such wheel. By means of the wheel, the line, the spring, the pawl, and the ratchet a much quicker velocity can be imparted to the rotary shear than can be effected by means of the crank turned by the hand of the operative. During the return motion of the wheel the pawl will slip over the teeth of the ratchet and produce no rotary movement of such ratchet.

By having on the shaft F the crank, as well as other mechanism, as described, for effecting the rotary motions of such shaft, we can often save the necessity of putting an undue strain on the line M, which is intended to be used for ordinary or light clipping, but when burrs or matted hair may become interposed between the shears and be of such nature as to cause an undue strain on the line, and which would tend either to injure or break it, we can use the crank in order to enable the shears to cut through the interposed matter or matters. Besides, in clipping or shearing the hair or wool of an animal it frequently occurs that the machine may be in positions where it would be inconvenient to rotate its shaft by the crank, such being the case when the machine may be inverted. Under these circumstances the line M may be used to advantage. So there are positions in which it becomes inconvenient for the operator to use the line M, in which case he can lay hold of and turn the crank. The gage-comb regulates the length to which the hair or wool is to be cut, and this may be varied in accordance with the distance at which the comb of the gage may be set from the stationary knife.

I do not claim a horse clipper composed of stationary and vibrating shears and a comb-gage; but

I claim as my invention—

1. My improved horse clipper or shears as made with the stationary and rotary shears D E, and with the gears H I and cranked shaft F, arranged and so as to operate together substantially as specified.

2. The combination of the same and the wheel L, the line M, the ratchet S, the spring-pawl R, and the spring O for operating the shaft F, as described.

GEORGE F. EVANS.
